CARL E. STEIGER, OF OSHKOSH, WISCONSIN, ASSIGNOR TO DELTOX RUG COMPANY, OF OSHKOSH, WISCONSIN, A CORPORATION OF WISCONSIN

WOVEN MATERIAL AND METHOD OF PRODUCING THE SAME

Application filed July 12, 1928. Serial No. 292,217.

My invention has relation to improvements in woven material and method of producing the same.

The invention contemplates, in its broadest aspect, the employment of two strands, one formed of a tough fibre, and the other of a material of greater diameter than the first-mentioned strand, the two strands being twisted together so that the one of greater diameter will extend radially outwardly beyond the strand of tough material, to form the wearing surface, while the latter strand will form an inner core or filling, the two strands so twisted together being particularly adapted for use as the weft thread for a rug, floor covering, or the like.

The invention also, in a more restricted sense, contemplates the employment of two strands for the use above indicated, wherein the strand of greater diameter is made up of a plurality of threads twisted together, a woolen strand being a generic example of a strand of this character, while the other strand is composed of a tougher material, such, for instance, as used in a cord formed from a twisted sheet of paper, the two strands referred to being twisted together so that the strand of greater diameter is caused to extend outwardly radially to a greater extent than the other.

In a still more restricted sense, the invention contemplates the employment of two strands, one composed of wool, and the other of paper or fibre, the said strands being twisted together so that the more bulky woolen strand will extend outwardly radially beyond the paper or fibre strand, the cord thus formed being used as a weft thread for a rug, floor covering, or the like, with the woolen strand forming the wearing surface and the paper or fibre strand forming the core or filler for the woolen strand.

Among the advantages attained by weft thread of the construction referred to, when woven to form a rug, floor covering, or the like, is economy in manufacture, and when wool is employed for one of the strands the appearance of an all-wool rug is obtained, while at the same time the springiness inherent in all-wool rug is also maintained.

In the accompanying drawing:

Fig. 1 is a plan view of a partly woven rug, two portions of the weft thread being pulled outwardly to show clearly the twisted together strands of the weft thread.

Fig. 2 is a cross-sectional view on the line 2—2 of Fig. 1; and

Fig. 3 is a view of the twisted together strands to form the weft thread.

Referring, first, to the more specific embodiment of my invention, the numeral 4 indicates the paper fibre strand of the improved weft thread, and 5 the woolen strand.

Fig. 3 of the drawing shows most clearly the form of the weft thread when the two strands thereof are twisted together, and by reference to this figure, it will be seen that the paper strand, which is more solid and stiffer than the woolen strand, forms in effect a core for the woolen strand, with the result that said woolen strand, owing to its fluffy character, due to the fact that it is formed of a number of threads twisted together, extends radially outwardly to a greater extent than the paper strand, and very materially obscures the paper strand, thus giving the appearance of an all-wool rug.

After the two strands are twisted together, they are put into a cop and woven into the form of a rug, floor covering, or the like.

Fig. 1 of the drawing, and the cross-sectional view, Fig. 2, show a partially formed rug. The warp strands of the rug are indicated by the numeral 6 and may be of any desirable material, such as paper fibre. The numeral 7 indicates end cross strands, formed of cotton or linen cords, or the like.

From Figs. 1 and 2, it will be seen that the twisted together strands 4 and 5 forming the weft are interwoven with the warp strands, so that each weft strand extends alternately over and under the warp strands. Owing to the fact that the wool strand is more bulky, or of greater diameter than the paper or fibre strand, and the latter strand is more solid or tougher than the wool strands, the latter necessarily, when the two strands are twisted together, projects outwardly radially from the paper strand, as indicated by the numeral 8, and thereby constitutes the wearing surface

of the rug, the paper strand forming an inner core or filler.

One of the important advantages, therefore, of my invention, particularly where the weft thread is composed of a wool strand and a paper or fibre strand, is that a rug in which such strand is used as a weft thread is not only much cheaper to manufacture than an all-wool rug, but also has the appearance of being made of all wool, and furthermore has the springiness of a wool rug, and necessarily, as the wool strand constitutes the wearing surface, the rug has better wearing qualities than a fibre rug.

15 As before indicated, while the improved weft thread is preferably made up of a wool strand and a paper or fibre strand twisted together, yet I do not desire to limit myself specifically thereto, inasmuch as the strand 4 instead of being of paper fibre may be of cotton, or like tough material and may be formed from a sheet of material twisted into cord-like formation. Also, the strand 5 may be of some other fabric, it only being essential that 20 it is more bulky than the strand 4, and is of such nature as to be capable of wrapping around the strand or core to form a projecting or outstanding wearing surface.

In this more broad aspect of the invention 30 certain of the advantages heretofore alluded to are equally present, i. e., economy in production, augmented wearing capability, and attractiveness in appearance, due to the fact that the strand which forms the core or filling is almost entirely obscured from view.

What I claim as my invention is:

As a new article of manufacture, a thread for use in the weaving of rugs, floor coverings, and the like, consisting of two twisted together strands of material, one strand being of soft yielding material, and the other strand being of a tough fibre material, the said strand of yielding material being of a diameter at least equal to the diameter of the other 40 strand and being of substantially the same length as said strand and the twisting together of the two strands producing a cord-like formation in which the strand of soft yielding material extends radially outwardly to a 45 greater extent than the tough strand, to constitute the wearing surface, and in which the tough strand forms an inner core or filling.

In testimony whereof, I affix my signature.

CARL E. STEIGER.
